COMBINATION FAUCET AND DRINKING FOUNTAIN

Charles L. Maguire, Yreka, Calif.

Application April 26, 1935, Serial No. 18,290

2 Claims. (Cl. 299—9)

This invention relates to a combination faucet and drinking fountain, the prime object of which is to provide a novel device of the character stated which will be effective in operation and inexpensive to manufacture.

A further object is to provide a novel combination mixing faucet and drinking fountain so arranged that water of different temperatures may be mixed but only the cold water can be admitted to the drinking fountain.

A feature of my invention is the novel needle valve in the drinking fountain duct whereby the quantity of water admissible to the fountain is controlled.

Another feature is the novel tapered regulating cock and a means to prevent pressure from building up between the body of the valve and the cock.

Other objects, advantages and features of invention may appear from the accompanying drawing, the subjoined detailed description, and the appended claims.

In the drawing:

Figure 1 is a top plan view of my combination valve and drinking fountain.

Figure 2 is a transverse sectional view of the same.

Figure 3 is an end view of the valve with parts broken away to show the construction of the drinking bowl.

Figure 4 is a sectional view taken on line 4—4 of Fig. 2, showing the tapered cock.

Figure 5 is an end view of the spring which presses against the cock to hold it on its seat.

Referring more particularly to the drawing, the numeral 1 indicates the valve body, and 2, the drinking fountain bowl which is integrally formed with the body 1. The bowl 2 is elongated substantially as shown, the water entering at one side and draining from the other, as will be subsequently described.

The body 1 is provided with a cold water intake 3 and a hot water intake 4. Suitable pipe fittings, which are usual and well known, extend to the intakes 3 and 4 for the purpose of conducting water thereto. If desired, valves 5 and 6 of usual and well known design may be provided in the intakes 3 and 4, respectively, for the purpose of controlling the quantity of water which enters said intakes. These valves may or may not be provided with handles, as desired. That is, the handles may be eliminated and the valves set at the points desired.

An outlet spout 7 is integrally formed with the

body 1, and the water from either or both of the inlets 3, 4 flows therethru. A tapered cock 8 fits closely within the bore 9 in the body 1. A detachable cover plate 10 closes the bore 9 and also holds the cock 8 in position. This cover plate is held in position by a plurality of machine screws, or the like. A stem 11 extends from the cock 8 thru the plate 10, and a control handle 12 is attached to the stem. The control handle rotates the cock 8 into various positions, as will be further described.

A spring pressed detent 13 mounted in the handle 12 will hold this handle in the various positions to permit water to flow to various positions, such as to the spout 7, or the fountain 2. The cock 8 is provided with a transverse bore 14. A second bore 15 extends from the bore 14 and this last named bore is adapted to communicate with the spout 7 to permit water to pass into said spout. By rotating the cock 8, the bore 14 can be brought into registry with either or both of the inlets 3, 4. When the bore is registering with both of the inlets, a mixture of hot and cold water is provided. The cock can also be adjusted to admit only hot or cold water to the spout.

A small angularly extending duct 16 is provided in the cock 8 for the purpose of admitting water from the cold water intake 3 to the drinking fountain. A duct 17 in the body 1 extends to one side of the bowl 2 and is directed longitudinally of the bowl so as to be available for drinking purposes. A control valve 18 in the duct 16 restricts the passage in the duct to the degree desired so that the proper amount of water will flow thru this duct and to the drinking fountain.

A vertical drain hole 19 extends from the bottom of the bowl 2 and thru the body 1 to discharge any excess water which flows into the bowl 2. The discharge 19 is at the opposite end of the bowl from the intake 17 and the discharge end is lower so that all of the water will drain from the bowl.

A multi-fingered spring 20 loosely encircles the stem 11 and is positioned between the cock 8 and the cover 10, thus pressing the cock into the body. Due to the tapered construction of the cock, the possibilities of leakage are prevented and also any wear is automatically compensated for. A bleed hole 21 extends from top to bottom thru the cock 8 for the purpose of equalizing the pressure on both sides of the cock and preventing the accumulation of water under pressure at the bottom of the cock, tending to unseat the same.

Having described my invention, I claim:

1. A combination faucet and drinking fountain comprising a body, a spout formed on the body, a conical cock rotatably mounted and seated in the body, said cock having a transverse bore extending therethru, said bore in the cock having intake passages therein, said bore in the cock being adapted to be brought into registry with the intake passages of the body, said cock having a second bore extending to the first named bore, 5 said second bore being adapted to be brought into registry with the spout whereby water flows from the faucet, a fountain bowl integrally formed on the body, a passage in the body extending into the fountain bowl, an angular duct in the cock, 10 said angular duct being adapted to be brought into registry with an intake in the body and the last named passage in the body whereby water flows into the drinking bowl, and a drain hole extending from the drinking bowl thru the body, 15 said drain hole being independent of the spout, said passage extending to the fountain bowl, entering at one side of the bowl and the drain hole being on the other side of the bowl.

2. A combination mixing faucet and drinking fountain comprising a body, a pair of oppositely disposed intake passages in the body, a spout formed on the body, a conical cock seated in the 20

25

body, a removable plate attached to the body and extending over the cock whereby the cock is held on its seat, a transverse bore extending thru the cock, said transverse bore being adapted to be selectively brought into registry with either of the intake passages of the body, a second bore in the cock extending from the first named bore, said second bore registering with the spout in the body, an angular duct in the cock, said duct being adapted to be brought into registry with only one 10 of the intake passages, a fountain bowl integrally formed on the body, a passage in the body extending to the fountain bowl, said angular duct being adapted to be brought into registry with the last named passage, said body having a drain 15 hole extending from the drinking bowl said drain hole being independent of the spout, a handle attached to the conical cock, and a bleed hole extending thru the cock, said bleed hole equalizing the water pressure on the top and bottom of 20 the cock to prevent unseating thereof, and a spring bearing against the cock and forcing same into its seat, said passage extending to the fountain bowl, entering the bowl at one side thereof, and the drain hole being on the other side of the 25 bowl.

CHARLES L. MAGUIRE.
